DOUBLE GLAZED WINDOW

Elmer H. Haux, Tarentum, Pa., assignor to Pittsburgh Plate Glass Company, Allegheny County, Pa., a corporation of Pennsylvania

Application May 15, 1937, Serial No. 142,796

2 Claims. (Cl. 20—56.5)

The invention relates to double glazed windows which ordinarily consist of two glass sheets or plates with a spacer between the edges of the sheet which also acts to seal off the space between the sheets from the atmosphere. The windows may be used in buildings or cars or in refrigerators and the present improvement is applicable in either relation, the cold side in a building being the outer one, and in a refrigerator the inner one.

One of the difficulties encountered with double glazed windows is the formation of condensation on the inner face of the sheet on the cold side of the window, which obscures the window and results in staining, due to the placing in solution of the alkali dust which accumulates to a greater or less degree on the faces of glass sheets not accessible for cleaning. It has been proposed heretofore to avoid this difficulty by placing dehydrating materials in communication with the space between the glass sheets and by making the spacer at the edges of the sheets as resistant as possible to the passage of moisture-laden air, but these expedients are only partially effective, as the dehydrators become exhausted and no practical sealing and spacing means has, as yet, been devised, which will prevent the infiltration of moisture-laden air therethrough.

It has also been proposed to overcome the difficulty by maintaining the space between the glass sheets in communication with the atmosphere on the cold side of the window. This is effective, since the air on the cold side of the window has a relatively low moisture content incident to its temperature and with a passage which permits of the circulation of such cold low-humidity air to the space between the glass sheets, there is no more tendency to condensation on the inner faces of the glass sheets than on their outer faces. The expedient has, however, the drawback that the passage to the space between the sheets permits the infiltration of cold air, thus reducing the insulating value of the glazing unit, and dust may be carried in with the air despite the use of filters of wool or the like for guarding against. Water may also be introduced through the passage in a driving rain or in washing.

The present invention is designed to obviate the objections incident to the use of dehydrators, and incident to the use of circulating passages. Briefly stated, this is accomplished by the use of a communication or passage leading from the space between the glass sheets to the atmosphere on the cold side of the window, in which a seal is provided of such character that it will prevent the passage of water as a liquid or of dust-laden

air, but which is readily permeable by water vapor. This is preferably accomplished by the use in the passage of a thin sheet or layer of cellulose acetate or other gas permeable material, such as cellulose ethers, synthetic resins, unglazed clay or the like which will seal against water, but are readily permeable by gases. Any leakage of moisture-laden air to the space between the glass sheets from the warm side of the unit, tending to increase the vapor pressure in the unit, will be taken care of by the more rapid release of vapor pressure through the gas permeable seal to the atmosphere on the cold side of the window, so that the vapor pressure of the air in the insulating space will be maintained at the same relatively low point as that of the atmosphere on the cold side of the window. There is thus (1) no condensation inside the unit with resultant possible staining of the glass, (2) no loss in insulation incident to the application of the expedient, and (3) no possibility of dust or water entering the unit. Certain embodiments of the invention are illustrated in the accompanying drawing, wherein:

Figure 1 is a side elevation of a car window equipped with the invention. Fig. 2 is a section on the line II—II of Fig. 1. Fig. 3 is an enlarged section through the end of the plug employed. And Fig. 4 is a section through a modification.

Referring to the drawing, 5 and 6 are glass sheets with an insulating space 7 therebetween; 8 is the frame of the window, and 9 is a spacer of insulating material, such as rubber having integral therewith channel portions in which the edges of the glass sheets are seated.

Secured to the corner of the frame is a casting 10 having a threaded recess carrying the hollow metal plug 11. A pair of passages (12 only one of which is shown) lead from the inner end of the threaded recess to rubber sleeves 13 mounted in recesses in the inner face of the casting. A pair of metal tubes 14 having heads 15 fitting into the rubber sleeves extend through the spacer to the space 7. Passages are thus provided from the space 7 to the space 16 at the end of the threaded recess.

The plug 11 is made tight by a rubber gasket 17 and has the inner end provided with perforations 18, as indicated in Fig. 3. The plug is filled with a body of glass wool 18a, and its outer end is closed with a screw cap 19 which serves also to hold in place on the plug a rotatable sleeve 20. The sleeve and side wall of the plug are provided with a pair of perforations, as indi-

cated at 21, which are in registration, as shown, when the sleeve is in one position of rotation.

The inner end of the plug is provided with a layer 22 (Fig. 2) of gas permeable material, such as cellulose acetate, preferably unplasticized, which forms a seal against the passage of water and dust between the interior of the plug and the insulating space 7. The glass wool 18a guards the layer of cellulose acetate against the direct impact of any water or dirt passing into the plug through the openings at 21. Any condensation forming in the plug will drain out through the openings, as they are located on the lower side of the plug. Since there is no chance of condensation within the glazing units during summer, the sleeve 20 may be turned during such period, so as to close the opening through the wall of the plug.

It will be seen that the construction described provides a communication from the insulating space 7 to the atmosphere which is interrupted completely against the passage of water, air and dust by the cellulose acetate or other equivalent layer 22, and it will be understood that this communication is to the cold side of the window, namely, to the outer side in buildings and the like, and to the inner side in refrigerators. As this layer is readily permeable by water vapor, the vapor pressure in the unit will be equalized with respect to that of the atmosphere with which it communicates. As a result, any vapor pressure which builds up in the space 7 incident to the infiltration of moisture-laden air through the spacer 9 from the warm side of the unit will be released. As the spacer 9 is made of material which will be most resistant to the passage of water vapor, and the layer 22 is of material which readily permits the passage of such vapor, the release of any vapor pressure which tends to accumulate will be rapid enough to permit the maintenance of a humidity in the space 7 approximately that of the atmosphere on the cold side of the unit. The rapidity of vapor transmission through the layer 22 depends on the composition, area and thickness, and these factors may be readily adjusted to give the desired rapidity of equalization, as even a layer of rubber may be used if it is made sufficiently thin. The insulating space 7 is completely guarded against access of dirt or water, and under extreme differences in temperature conditions on opposite sides of the unit, no condensation occurs on the inner surface of the glass sheet 6 which is the one subject to this difficulty in previous constructions. It will be understood that the invention is equally applicable to triple glazing and that the term "double glazed window" is generic to windows having two or more panes.

The invention is capable of embodiment in a

wide variety of structures, of which Fig. 4 is illustrative of a form in which the gas permeable sealing means for the passage leading to the cold side of the window is located in the edge of the sash, instead of in a plug extending from the side thereof as heretofore described. In this structure, 23 is the car frame carrying the metal sash frame made up of the parts 24, 25 and 26, similar to that of the Fox and Stroud Patent No. 2,054,856, the sash being cushioned and held in place in the car frame by the rubber strip members 27 and 28. A tube 29 leads from the space 30 between the panes 31 and 32 and terminates in a recess 33 of circular cross section at the edge of the sash. This recess opens into a slot 34 which communicates through a passage 35 with a slot 36. Holes 37 lead into the slot 36 from the atmosphere on the outer side of the window. A communication is thus provided from the outer atmosphere to the insulating space 30 between the panes of glass. The recess 33 carries a pair of perforated metal discs 38 and 39 yieldingly held in place frictionally, and between these discs is a body 40 of mineral wool or similar material. The face of the disc 39 is covered with a layer 41 of a gas-permeable material, such as the cellulose acetate layer 22 of Fig. 3; and this functions in the same manner as the layer 22, forming a seal against the passage of water or dirt, but permitting the equalization of the vapor pressure in the space 30 with that of the outer atmosphere.

What I claim is:

1. In a double glazed window construction which includes a sash having a passage therein opening to the atmosphere and leading therefrom to the space between the panes of the window, a filter in the passage comprising a foraminous support extending across the passage, a layer of solid, non-fibrous material back of the member which is a positive seal against water as a liquid and against dust but which is readily permeable by water vapor, and a body of fibrous screening material in the passage back of said layer of material.

2. In a double glazed window construction which includes a sash having a passage therein opening to the atmosphere and leading therefrom to the space between the panes of the window, a filter in the passage comprising a hollow metal plug screwed therein with a communication to the atmosphere at its outer end and having a foraminous plate at its inner end, a layer of solid, non-fibrous material back of the plate of a composition which is a positive seal against water as a liquid and against dust but which is readily permeable by water vapor and a body of fibrous screening material in the plug back of said layer of material.
